UNITED STATES PATENT OFFICE

147,223

DESIGN FOR PAPER OR THE LIKE

Errington A. Whiteford, Darien, Conn.

Application September 20, 1946, Serial No. 133,441

Term of patent 3½ years

(Cl. D59—2)

To all whom it may concern:

Be it known that I, Errington A. Whiteford, a citizen of the United States, residing at Darien, in the county of Fairfield and State of Connecticut, have invented a new, original, and ornamental Design for Paper or the like, of which the following is a specification, reference being had to the accompanying drawing, forming a part thereof.

The figure is a plan view of a sheet of paper showing my new design.

The design unit is contained between the dot and dash lines and is repeated continuously as indicated by the extensions beyond the unit boundaries.

I claim:

The ornamental design for paper or the like, as shown and described.

ERRINGTON A. WHITEFORD.
